UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

INKING MECHANISM FOR PRINTING-PRESSES.

1,301,091.

Specification of Letters Patent. Patented Apr. 22, 1919.

Application filed April 26, 1916. Serial No. 93,697.

To all whom it may concern:

Be it known that I, HENRY F. BECHMAN, a citizen of the United States, residing at Battle Creek, in the county of Calhoun and 5 State of Michigan, have invented certain new and useful Improvements in Inking Mechanism for Printing-Presses; and I hereby declare that the following is a full, clear, and exact description thereof, reference being had to the accompanying drawings, which form part of this specification.

This invention relates to printing presses and has particular reference to the inking mechanism thereof; and is especially designed for use with so called rotary presses, but is also adapted to other types of presses wherein a very fine and uniform distribution of ink is desired.

The object of the invention is to provide 20 a primary distribution of the ink after it is taken from the fountain and before it is delivered to the distributing drum or system of distributing rollers; and to accomplish this I provide a distributing table between the ink fountain and the drum and a reciprocating ductor, or ductors, to take ink from the fountain and deliver it to the table and primarily distribute the ink thereon before the ink is delivered to the drum; so that 25 instead of the drum receiving the ink in daubs from a line on the periphery of the ductor, it receives it practically uniformly distributed upon the periphery of the ductor. Preferably I employ two ductors, one of 30 which takes ink from the fountain and supplies it to and distributes it on the table as stated, and the other of which assists in distributing the ink on the table and also delivers it from the table to the ink drum. The 35 essentially novel feature of the invention is the provision of a distributing table between the ink fountain and the ink drum.

In the accompanying drawings I have 40 illustrated one embodiment of the invention as applied to the inking mechanism of a rotary press, and will explain the invention in connection therewith to enable others skilled in the art to adapt and use the same; but I do not consider the invention restricted 45 to the particular construction or arrangement of parts shown, and refer to the claims for concise definitions of the novel invention for which protection is desired.

The accompanying drawing represents a 50 diagrammatical sectional elevation of a ro-

55 tary printing couple and inking mechanism therefor equipped with the invention.

In said drawings 1 designates a plate cylinder; 2 the impression cylinder; 3 the form rollers; 3^a the intermediate rollers taking 60 ink from the distributing rollers 4^a, which receive ink from the drum 4 in the usual manner; and 4^b are distributing rollers or vibrators arranged to contact with the periphery of the drum 4 and disseminate the 65 ink thereon in the usual manner. 6 is the ink fountain. All the aforesaid parts may be of the usual or any preferred construction and will be readily understood by pressmen.

Intermediate the fountain 6 and the drum 70 4, is a primary distributing table 5. Operating upon the table 5 and between the drum 4 and fountain 6 is a reciprocating ductor 75 roller or rollers, two preferably being used. These ductor rollers 7 and 8 are designed and adapted to be rolled back and forth over the table 5 and between the drum 4 and fountain 6 by any suitable means (not shown) such as may be preferred by the designer and best suits the general arrangement or construction of the press with which the invention is used.

In the example shown the ductor roller 7 is adapted to take ink from the fountain roll 6^a and supply it to the table 5 and to also cut 85 up or distribute the ink on said table 5 as the ductor rolls thereover. The ductor roller 8 preferably travels with the roller 7, and assists in distributing the ink on table 5, and also transfers ink from the table 5 to the 90 drum 4.

It will be seen that with such construction and arrangement of parts the ink taken from the fountain 6 will be primarily distributed on the table 5, and will be practically uniformly applied to and around the periphery of the ductor roller 8 before the latter contacts with the drum 4; consequently when the drum 4 contacts with ductor 8 it receives ink therefrom in a substantially uniformly distributed condition; and such ink is thereafter more easily quickly and thoroughly disseminated on the surface of the drum by the vibrators 4^b before it is taken from the drum by the rollers 105 4^a. As a result of this manner of supplying ink to the drum, a much superior distribution of ink and more uniform application thereof to the form rollers is obtained, resulting in a better quality of printing.

By using this invention a superior ink distribution can be produced with the same number of rolls than has hitherto been possible; or as good distribution of ink can be obtained with a less number of rolls than has been hitherto possible. The invention is particularly useful for fine press work where it is essential that the ink shall be most thoroughly and uniformly distributed before it is applied to the form rollers.

What I claim is:

1. Inking mechanism for printing presses, comprising an ink drum and co-acting rollers, an ink supply, an ink distributing table intermediate the fountain and drum, and two reciprocating ductor rollers respectively adapted to take ink from the fountain and distribute it upon said table and to take ink from the table and deliver it to the drum.
2. In inking mechanism for printing presses, the combination of ink distributing means, an ink supply fountain, a distributing table intermediate the supply and distributing means, a pair of ductor rollers adapted to operate upon said table between the supply and the distributing means, one of the ductor rollers taking ink from the

supply and delivering it to the table, and the other ductor roller delivering ink from the table to the distributing means.

3. In inking mechanism for printing presses the combination of an ink drum and co-acting distributing rollers; an ink fountain, a distributing table intermediate the fountain and the drum, a pair of reciprocating ductor rollers adapted to operate upon said table between the fountain and the drum, one of the ductor rollers taking ink from the fountain and delivering it to the table, and the other ductor delivering ink from the table to the drum.

4. In inking apparatus for printing presses, the combination of a set of distributing rollers, a fountain, a table intermediate the fountain and distributing rollers, and a pair of reciprocating ductor rollers one of which takes ink from the fountain and the other delivers it to the distributing rollers, both said ductors distributing ink upon the said table.

In testimony that I claim the foregoing as my own, I affix my signature.

HENRY F. BECHMAN.
